RACK

Alexander L. Feldman, Bronx, N. Y.

Application March 6, 1952, Serial No. 275,062

2 Claims. (Cl. 211—60)

1

This invention is concerned with racks for holding elongated objects such as knives, forks and spoons, and the principal object of the invention is to provide a simple, sturdy, economically constructed rack in which silverware can be washed, rinsed and dried vertically, without danger of jamming the silverware into an unworkable mass, or of losing the silverware through the openwork necessary for proper drainage and evaporation. In particular, my invention provides a rack for silverware which can be used either in a mechanical dishwasher or in a sink, and which can be used to dry and store silver between usings.

My invention can best be understood by reference to the accompanying drawings, in which

Figure 1 is a perspective view of one form of my device constructed of sheet metal;

Figure 2 is a partially broken side view of Figure 1;

Figure 3 is a perspective view of an alternative form of bottom incorporating the principle of my invention;

Figure 4 is a cross section through line 4—4 in Figure 3;

Figure 5 is a top plan view of a section of a ring used to make another form of my device which can be constructed from plastic;

Figure 6 is a cross section through the line 6—6 of Figure 5, showing how a completed unit would look;

Figure 7 is a top view of the plastic bottom #37 in Figure 6.

Referring to the drawings, my rack is essentially an elongated open cylinder with a preferably foraminous bottom, and a handle at the top, with sides comprising rings which are truncated inverted conic sections. Preferably, the interior of the cylinder is divided into a number of vertical sections by vertical partitions. The inverted truncated conic rings are so spaced with relationship to each other that pieces of silverware pushed into the holder from the top, will, when they just clear the bottom of one ring, hit the surface of the ring just below it, even though there is a considerable open vertical space between the bottom of one ring and the top of the next. This is, of course, due to the inward slant of the ring sections.

Referring more particularly to Figures 1 and 2, the rack may be built about a pair of sheet metal cross pieces 10 and 11, made by folding two pieces of sheet metal and fastening them to the handle member 13 passing through the center of the rack. A circular flat disc 14, is

secured to the bottom of the cross pieces 10—11; holes 15 cut in the bottom disc 14, provided for adequate drainage. Preferably, the disc 14 is spaced from any surface on which it may rest by providing a ring 16 about its periphery, at right angles to the disc; this entire piece can be stamped out of a large disc, and formed in a single operation.

An alternative method of constructing the bottom is shown in Figures 3 and 4. Inclined slats 43 are used. This design incorporates the principle of the invention in the construction of the bottom as well as the sides.

Also, the bottom may be designed as a solid piece, with a slight pitch from the center to the sides, whereby drainage is ensured through the bottom opening 18.

At calculated intervals between the disc 14, forming the bottom of the rack, and the top of the cross pieces 10 and 11, there are disposed rings 17, whose construction and disposition are vital to the success of my new rack. These rings are essentially inverted conic sections; they are laid around and attached to the cross pieces at their extremities, with openings 18 between them to provide for drainage, ventilation and easy passage of fluids. In order to ensure that pieces of silverware will automatically stack correctly in the rack, the rings are so related to each other that a straight line drawn from the crossing point 19 of the pieces 10 and 11, through the bottoms 20, 21, 22, 23 and 24 of any of the rings, will strike the ring below it. Hence, if silver is put into the rack, a piece striking the top ring will be deflected downward by the inwardly slanting surface of the inverted conic section which comprises the ring; it will slide past the point 20 and strike the ring, past the point 21 and strike the next ring, and so on until it hits bottom, where it belongs. There are no drainage holes into which it can hit and be caught in and at the same time a large space is provided to permit air and fluid circulation.

Another form of the device is illustrated in Figures 5, 6, 7. This form of the device can be made from molded plastic. Here the rack consists of a group of identical sections, each consisting of a cross shaped piece 31, the arms of which are inverted wedges, with a narrow top portion 32 and a wider bottom portion 33; these pieces correspond to pieces 10 and 11 of the first form of the device. The merit of the wedge cross section shape is that objects cannot catch in any spaces between the arms, the principle being similar to that used in the ring design.

At both ends of one of the arms, the piece is enlarged to form end portions 34, through which holes 35 are drilled or cast. The circumference about this cross piece is partially filled by a ring 36, which is an inverted truncated conic section with its base on the circumference of the top of the section, but truncated well above the bottom of the section, to provide an opening between the bottom of the ring and the bottom of the section.

These sections are joined together with a bottom disc 37 having holes 38 therein and leg members 39, by means of a handle member 40 having legs 41 which fit into holes 35 in the end portions 34. Flattened spots in the legs 41 and washers 42 hold the top section; while wing nuts 43, on the threaded bottoms 44 of the legs 41 hold the assemblage together.

It will be seen that this form of the device, like that shown in Figures 1 and 2 will automatically force flatware down to the bottom.

Both forms of the device can be styled to provide handsome water resistant racks which can be used both for washing, draining, drying and storage. Furthermore, they are so largely open that the device can be used in mechanical dishwashers as well as in ordinary dishwashing. The sides of the rings will serve to deflect the stream of water downward along the objects tending better to remove particles from them. Because 30 the pieces are held vertically, they drain properly, and dry without the spots which gather on flatware which is allowed to drain in the conventional horizontal position.

Obviously while the device has special utility for washing flatware, its use is not restricted thereto. The rack could be used for storing

any rigid elongated object where circulation of fluid past the object—for washing, drying, aeration, etc.—is desired.

While I have described my rack as a cylinder, it could obviously be of any cross-sectional shape, although I prefer the cylinder shape because there are no corners in which to catch and insertion into the washing cylinder is easier.

I claim:

- 10 1. A rack for holding elongated objects while exposing them to fluid action, comprising a vertically elongated hollow body open at the top, and consisting of a skeleton frame holding a bottom member and a plurality of side wall members disposed around the periphery of the hollow body and vertically spaced from each other, to provide openings in the sides of the rack, the side members extending inwardly and downwardly from the side walls for a sufficient distance so that a straight line drawn from any point in the open top of the rack will strike the frame, a side member, or the bottom member.
- 15 2. The rack of claim 1 in which the rack is divided into compartments by a series of cross shaped members the arms of which are inverted wedges in cross section.
